DESIGN FOR A SLIP OR SIMILAR ARTICLE

David Levy, New York, N. Y.

Application December 17, 1937, Serial No. 73,680

Term of patent 7 years

To all whom it may concern:

Be it known that I, David Levy, a citizen of the United States, residing in New York city, county and State of New York, have invented a new, original, and ornamental Design for a Slip or Similar Article, of which the following is a specification, reference being had to the accompanying drawing, forming a part thereof.

Fig. 1 is a front view of a slip or similar article, showing my new design.

Fig. 2 is a back view thereof.

The essential feature of the design resides in the specific ornamentation and its arrangement on the upper portion of the garment, substantially as shown.

I claim:

The ornamental design for a slip or similar article, substantially as shown and described.

DAVID LEVY.
